UNITED STATES PATENT OFFICE.

HORACE L. HEATON, OF INDIANAPOLIS, INDIANA, ASSIGNOR OF ONE-HALF
TO FRANK WOODBRIDGE, OF SAME PLACE.

COMBINED LOCK AND LATCH.

SPECIFICATION forming part of Letters Patent No. 308,559, dated November 25, 1884.

Application filed February 27, 1884. (No model.)

To all whom it may concern:

Be it known that I, HORACE L. HEATON, a citizen of the United States, and a resident of Indianapolis, in the county of Marion and State of Indiana, have invented certain new and useful Improvements in Door Locks and Latches; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved latch and lock. Fig. 2 is a similar view of the same with one side of the casing removed. Fig. 3 is a horizontal section on line *x x*, Fig. 1. Fig. 4 is a similar view on line *y y*, Fig. 1; and Fig. 5 is a detail view of the tumbler.

Similar letters of reference indicate corresponding parts in all the figures.

My invention has relation to that class of locks and latches in which a gravitating arm connected to the lock-spindle and having a projecting lug engages a notch in the main bolt, with the said lug forcing it outward, and in which a tumbler operated by the key may engage projections or shoulders upon the main bolt, locking the same; and it consists in the improved construction and combination of parts of such a lock and latch, consisting of a gravitating bolt pivoted upon the lock-spindle and engaging a notch in the main bolt by an upwardly-projecting lug, and of a sliding tumbler adapted to be operated by the key, and to bear against a shoulder at the outer portion of the main bolt, as hereinafter more fully described and claimed.

In the accompanying drawings, the letter A indicates the lock-casing, which may be constructed so as to be secured upon either side of the door or to be inserted into a mortise, as desired, and the main bolt B slides with its outer end, which may be square or beveled, as desired, in a slot, C, in the forward side of the lock-casing, and slides with its inner portion upon a lug, D, projecting into a longitudinal slot, E, in the inner portion of the bolt. The forward or outer end of the bolt

forms shoulders F, the inner portion of the bolt, or the portion within the casing, being reduced, and the rear end of the bolt has two notches or recesses, G, one extending from each edge. An upwardly-projecting lug, H, projecting from the inner portion of a gravitating arm, I, pivoted within the casing, projects into the notch or recess upon the lower edge of the bolt, and the weight of the forwardly-projecting arm will force the lug, and through it the bolt, forward. The gravitating arm forms at its fulcrum two laterally-projecting round lugs, J, which project through and turn in perforations K in the sides of the lock-casing, and the lugs and the end of the arm from which they project have a perforation, L, preferably square, through which a correspondingly-shaped lug, M, projecting inward from the end of an arm, N, projects and fits. This lug has a central female threaded perforation, O, into which the inner threaded end, P, of the spindle Q fits and turns, and the said threaded end of the spindle is prevented from turning in its perforation when screwed home by means of a screw, R, passing through a threaded perforation, S, in the arm and lug eccentric to the other perforation, but entering the side of the said perforation; and the threaded end of the spindle has a correspondingly-threaded groove or recess, T, at the side facing the portion of its perforation opening into the other perforation, so that the securing-screw R fits partly in its perforation in the arm and the lug and partly in the threaded groove in the end of the spindle. The other side of the threaded perforation S for the securing-screw is also open, and the adjoining side of the square perforation in the gravitating arm has a groove or recess, U, having a portion of a screw-thread corresponding to the thread of the perforation, and the securing-screw will thus bind the spindle, the gravitating arm, and the inwardly-projecting square lug together. I wish, however, to state that the spindle or operating-arm may be connected to the gravitating arm in any other suitable manner without departing from the spirit of my invention. V is a tumbler having a reduced rear or in-

ner end, W, which slides upon a stud, X, projecting from the inner side of the casing, and the forward or outer portion of the tumbler is enlarged, as shown at Y, and has a longitudinal slot, Z, having two notches, A', one at each end, and has a notch or recess, B', in its lower end, in which the bit of a key, C', may engage, raising the tumbler and causing one of the notches in the slot to be raised off a stud, D', upon the inner side of the casing, upon which stud the slot slides, thus allowing the bit of the key to slide the tumbler. The forward end of the tumbler may, when the tumbler is slid forward, be brought to bear against one of the shoulders upon the sides of the bolt, thus preventing the bolt from being drawn inward, the bolt being reversible, so as to bring its beveled side, when it is beveled, to either side. An arm, E', may be secured to the upper edge of the tumbler, projecting up through a slot, F', in the upper side of the casing, by means of which arm the tumbler may be operated; and when this arm is used a catch, G', may be pivoted upon the upper side of the casing, turning, with its downwardly-projecting lug H', in a slot or perforation, I', and may be brought to bear against the upper end of the arm, when the latter is thrown in its forward position, preventing the arm from being thrown back, and through it preventing the tumbler from being slid back, thus forming a dead-latch. The inner side of the lower side piece of the casing is provided with a rubber or other elastic cushion or spring, against which the weighted arm may bear when tilted down. It follows that the forwardly-projecting weighted portion of the gravitating arm may be dispensed with and the operating-arm may be weighted in its place, and that the relative position of the lug projecting into the notch in the bolt and of the weighted arm may be changed according to the direction in which the bolt is to be forced and according to the position of the casing.

Having thus described my invention, I claim and desire to secure by Letters Patent of the United States—

1. The combination, in a lock, of a bolt having its inner end reduced, forming shoulders at its outer end, and having a notch in its edge, a gravitating arm having a lug projecting into the notch, and having means for rocking it, and a tumbler having a longitudinal slot forming notches in both ends and sliding upon a pin, and having means for throwing it

forward, bearing against the shoulder of the bolt, as and for the purpose shown and set forth.

2. In a lock and latch, the combination of a sliding bolt having its inner portion reduced, forming shoulders at its outer portion, and having notches in the rear ends of its edges, a gravitating arm having a lug engaging one of the notches in the bolt, and having means for rocking it, and a tumbler sliding, with a longitudinal slot forming notches at both ends, upon a pin, and having a notch or recess in its lower edge for the bit of the key adapted to be thrown forward to bear against one of the shoulders of the bolt, locking it, as and for the purpose shown and set forth.

3. In a lock and latch, the combination of a sliding bolt having its inner portion reduced, forming shoulders at its outer end, and having notches in the rear ends of its edges, a gravitating arm having a lug engaging one of the notches in the bolt, and having laterally projecting trunnions at one end turning in the lock-easing, and provided with an operating-arm and with a handle, and a tumbler sliding, with a longitudinal slot forming notches at both ends, upon a pin having a notch or recess in its lower edge, and provided with an arm secured to its upper edge and projecting through the upper side of the casing.

4. The combination of the gravitating arm having trunnions rocking in the sides of the casing, the said trunnions having a square perforation with a threaded groove in one side, an operating-arm having a square lug fitting into the perforation, and having a central threaded perforation entering it at its inner end, and an eccentric threaded perforation opening at one side into the central perforation and at the other side into the groove in the square perforation, a spindle having its inner threaded end fitting into the central threaded perforation, and having a threaded groove in one side, and a securing-screw passing through the eccentric perforation and fitting into the female threaded grooves in the end of the spindle and in the square perforation, as and for the purpose shown and set forth.

In testimony that I claim the foregoing as my own I have hereunto affixed my signature in presence of two witnesses.

HORACE L. HEATON.
